UNITED STATES PATENT OFFICE.

JOHN FLANAGAN, OF NEWBURG, NEW YORK, ASSIGNOR OF ONE-HALF TO
JAMES C. GRIGGS, OF SAME PLACE.

WATER-CLOSET AND BIDET BOWL.

SPECIFICATION forming part of Letters Patent No. 244,219, dated July 12, 1881.

Application filed April 13, 1881. (No model.)

To all whom it may concern:

Be it known that I, JOHN FLANAGAN, of Newburg, in the county of Orange and State of New York, have invented a new and useful Improvement in Water-Closet and Bidet Bowls, of which the following is a specification.

Figure 1 is a perspective view of my improvement. Fig. 2 is a plan view of the same, partly in section. Fig. 3 is a top view of the same, showing the flaps and cut-away portion corresponding with the bidet-recesses.

Similar letters of reference indicate corresponding parts.

The object of this invention is to promote convenience in using and in ventilating bidet and water-closet bowls.

The invention consists in constructing a water-closet and bidet bowl with recesses in its rim to allow the hand to be introduced for bidet purposes; also, in constructing the trunk or pot with embossments upon the opposite sides of the lower and upper parts to receive inlet and outlet air-pipes for ventilating the said trunk; and, also, in the combination, with the air-outlet pipe, of the T branch, whereby the space below the water-closet seat is ventilated, as will be hereinafter fully described.

A represents a water-closet bowl, which is connected with and secured to a trunk or pot, B. The rim of the bowl A is turned down inward, as in the bowl known as the "French" bowl.

In the rim of the bowl A are formed three recesses, C, one directly in front and the other two upon the opposite sides of and equally distant from the first or front recess. The recesses C are made of sufficient size to allow the hand to be inserted for bidet purposes, and the cover is provided with hinged flaps corresponding in position with rear recesses, and is cut away over the front recess. The recesses C can be applied to bowls of various shapes.

Upon the opposite sides of the upper and lower parts of the trunk or pot B are formed embossments D, with one of the lower ones of which is connected the end of an inlet air-pipe, E, which passes out through a sidewall of the

building, so as to admit cold air into the said trunk or pot B.

With the upper embossment, D, upon the opposite side of the trunk B from the inlet-pipe E, is connected an outlet air-pipe, F, which passes up through the roof, and is bent over or is supplied with a suitable ventilating-cowl. The embossments D with which pipes are not connected are closed. The object of having embossments upon the opposite sides of the top and bottom parts of the trunk B is to allow the pipes to be applied to either side of the trunk, as the situation of the side walls of the building may render most convenient.

To the outlet-pipe F, below the seat of the water-closet, is attached a T branch or coupling, G, with a large opening, as shown in Fig. 1, to ventilate the space below the said seat.

The inlet air-pipe E is designed to be supplied with a stop-cock having a branch or third opening, so that in cold weather, when there would be danger of the freezing of the water in the trap, the stop-cock can be closed to shut out the cold air and the ventilating circulation obtained through the branch of the said stop-cock from within the house. The stop-cock is not shown in the drawings.

In the rear side of the upper part of the bowl A, beneath the turned-over rim, is formed the inlet or arm H, to receive the end of a pipe for introducing water for the afterwash, which pipe is provided with a valve connected with and operated by the rod that works the bottom valve of the bowl A.

The water-pipe and its valve are not shown in the drawings, as there is nothing new in their construction.

Having thus fully described my invention, I claim as new and desire to secure by Letters Patent—

1. A water-closet and bidet bowl constructed with recesses in its rim, substantially as herein shown and described, to allow the hand to be introduced for bidet purposes, as set forth.

2. In a water-closet and bidet bowl, the trunk B, constructed substantially as herein shown

and described, with embossments D upon the opposite sides of its lower and upper parts to receive the inlet and outlet air-pipes E F, whereby the said trunk is ventilated, as set forth.

3. In a water-closet and bidet bowl, the combination, with the outlet air-pipe F, of the T

branch G, substantially as herein shown and described, whereby the space below the water-closet seat is ventilated, as set forth.

JOHN FLANAGAN.
